AUTOMATIC GUN

Halvor Olsen Eiane, Washington Island, Wis.

Application June 7, 1938, Serial No. 212,230
In Canada August 6, 1937

6 Claims. (CL. 42—3)

My invention relates to improvements in gas operated guns in which a portion of gases from a fired charge in a barrel is utilized as motive power for operating a piston in a cylinder connected to a breech mechanism, and the objects of my improvements are, first, to provide means for entrapping a sufficient quantity of gas in a special reservoir to enable a piston in a cylinder to operate a connected breech mechanism; second, to provide means for automatic filling and closing of the gas reservoir to enable the bore of a barrel to discharge its gases before the piston in the cylinder is set in motion by gas pressure from the reservoir; and third, to prolong the life of the mechanism by reason of elimination of the sharp blows incidental to operation on the impulse principle employed in other guns.

I attain these objects by means of an automatic power mechanism embodying in parts the main principle of my earlier application for patent on an Automatic rifle, filed June 1, 1936, Serial No. 82,811, and further embodying improvements as shown and described in my applications for patents on an Automatic firearm, filed in Canada, Aug. 6, 1937, in Great Britain, Aug. 10, 1937, and in France, Aug. 25, 1937, together with a few later improvements hereinafter more fully described and claimed, having reference to the accompanying drawing in which Fig. 1 represents a longitudinal partly sectional side view of the assembled power mechanism in attached relation to the barrel, through a projecting valve-housing.

Fig. 2 is an enlarged sectional side view of the piston taken along its longitudinal center, where the main body of the piston is split into two halves, and shows a piston-rod joined to the piston.

Fig. 3 is an enlarged sectional side view of a spring-pressed check-valve, shown in its supporting sleeve, in detached relation.

Fig. 4 is a cross sectional view of an auxiliary exhaust valve, taken adjacent to the face of the valve.

Fig. 5 is an enlarged sectional side view of a tubular-shaped relief valve, shown in detached relation and carrying the auxiliary exhaust valve within its body.

Fig. 6 is a bottom plan view of the projecting valve-housing on the barrel, showing the valve plug removed.

Fig. 7 is a top plan view of a control valve, showing its hinged lever slightly inclined so a second ear thereon appears in the view.

Fig. 8 is a top plan view of the valve plug,

showing a plurality of gas vents in its upper edge.

A, in Fig. 1, is part of a gun barrel which is provided with a projecting valve-housing 2. Into the projecting valve-housing 2 is screwed a cylinder 3, in which a piston 4 is adapted to move back and forth. The piston 4 is universally joined to a piston-rod 5 by means of a ball-shaped terminal 6 carried at the front end of the piston-rod 5, which fits movably in a ball-socket 7 located in the rear portion of the piston 4.

A main action spring 8 is mounted on the piston-rod 5 and within the cylinder 3. The front end of the spring 8 abuts against the rear end of the piston 4, while the rear end of the spring abuts against a cap 9 screwed onto the rear end of the cylinder 3.

At the forward end of the projecting valve-housing 2 is a cylindrical gas-reservoir 10 screwed into said housing and the joint permanently secured by solder or similar means as there will be no further need for dismantling this particular part of the structure.

At the front end of the reservoir 10 is a reduced section 11 in which is located a valve seat 12. Upon the seat 12 rests a tubular-shaped relief valve 13, which at its opposite end away from the seat is provided with a flange 14, adapted as a shoulder for a spring 15. A cap 16 is screwed onto the front end of the reservoir 10 and serves as an abutment for the spring 15, which in turn presses the valve 13 against the seat 12.

Referring to Fig. 5, it will be seen that the relief valve 13 carries within its body an auxiliary exhaust valve 17, which normally is held open by the spring 18, while a nut 19 limits its opening. A section 20 of the valve 17 is milled triangular in cross section (Fig. 4), so as to provide passages for gases to flow through the section 20, thence through vents 21 in the valve 13 and finally out through vents 22 which communicate with the atmosphere.

Referring again to Fig. 1, it will be seen that a passage 23 communicates between the bore 24 and the cylinder 3 and the reservoir 10. In the passage 23 is located a control valve 25, by which means the passage 23 can be closed or opened to any degree as desired.

The valve 25 is provided with a semi-circular collar 26 (Fig. 7), which is received by the semi-circular recess 27 (Fig. 6) and thus maintains the valve in position against lateral end play. A lever 28 is hinged at 29 (Fig. 7) to a hub 30 of the valve 25, by which means the valve may be turned to any position as desired. The hinged

lever 28 is provided with a lock-point 31 at its inner side and a pair of projecting ears 32 on its opposite side which are spaced apart to accommodate a spring 33 tending to press the lever 28 inward so that the lock-point 31 will engage radial locking pockets in a locking dial, which however is no part of the present invention.

At the lower end of the communicating passage 23 (Fig. 1) is located an inverted tumbler-shaped check-valve 34 which normally closes the passage. The valve 34 is supported in a guide-bushing or sleeve 35 which is screwed into the valve-housing 2 from the bottom side thereof and permanently secured thereto by means of soldering.

Referring to Fig. 6, it will be seen that the guide-sleeve 35 is provided with a plurality of grooves 36 in its inner walls which serve as gas vents to equalize the gas pressure between the exterior and the interior of the valve 34, so that the valve is thereby always free to function.

A plurality of radially disposed grooves 37 (Fig. 8) in a plug 38 are in alignment with the grooves 36 when the plug 38 is screwed into its proper place in the guide-bushing 35, and the gas vents communicating between the exterior and the interior of the valve 34 are then complete.

The plug 38 serves as an abutment for a spring 39 which presses the valve 34 against its seat in the lower end of the communicating passage 23, which thereby is hermetically sealed.

A comparatively large longitudinal passage 40 in the valve-housing 2 communicates between the interior of the cylinder 3 and the gas-reservoir 10, and this passage is further enlarged around the guide-sleeve 35.

Referring more particularly to Fig. 2, it will be seen that the piston 4 is of a novel design and construction, in which the main body of the piston is split longitudinally into two equal halves 40 so that the ball-socket 7 in each half part will form a perfect bearing for the ball terminal 6, located on the forward end of the piston-rod 5. It will be further seen that the main body 4 of the piston is provided with a reduced section 4A, upon which are placed bull-rings to keep the two halves of the piston 4 together.

A squeezer bull-ring 41 is placed next to the socket 7 to squeeze the two halves of the piston 4 together; next are placed three or more bull-rings 42 over the reduced section 4A, and each bull-ring 42 carries an expansion ring 43. A nut 44 squeezes the bull-rings and the two piston halves together, and the nut is then locked by means of a split-key (not shown) which is inserted in the hole 45.

When a charge of gunpowder is fired in the barrel A, a projectile or bullet is forced out through the bore 24 and at the instant the bullet passes the communicating passage 23, gases will force the check-valve 34 open and fill the gas-reservoir 10 and simultaneously close by gas pressure the auxiliary exhaust valve 17.

If the gas pressure in the reservoir 10 is excessive the relief valve 13 will lift off its seat and the excessive gases escape out through the vents 22. At a point where the gas pressure in the bore 24 is near to the pressure in the reservoir 10, the check-valve 34 will instantly close the passage 23 by reason of stored power in the spring 39.

Inertia of the breech mechanism to which the piston-rod 5 will be connected, in addition to pressure exerted thereon from the bore 24, will cause the piston 4 to delay its movement until the pressure in the bore is nearly down to the zero mark, at which time a full head of gas pres-

sure in the reservoir 10 will force the piston 4 out through the cylinder 3. When the piston 4 has passed the main exhaust port 46, the gases in the cylinder 3 and the reservoir 10 will pass out to the atmosphere.

In the meantime, the spiral spring 8 has been compressed and the piston 4 will, by means of this compressed spring, return to its starting point in the cylinder 3 together with the piston-rod 5 and its further connected breech mechanism. As the piston 4 returns to its normal position, gases collected in front of the piston will pass out through the auxiliary exhaust valve 17 which opens when the pressure in the reservoir is reduced to near the atmospheric pressure.

The cylinder cap 9 and the spiral spring 8 are placed on the piston-rod 5 prior to assembling the piston 4 on the terminal ball 6.

Referring further to Fig. 1, it will be noted that the cap 16 screwed onto the reservoir 10 is provided with a flange 47, which is intended for the purpose of retaining a front barrel band, when this power system is used in connection with military rifles.

Although this invention is primarily intended for use in connection with my earlier invention heretofore referred to in this specification, it is none the less my intention to use it in connection with any other guns which operate on the gas power principle, be it a small gun carried in the hand or a big gun mounted on a carriage.

Having thus described my invention, what I claim as new and desire to secure by Letters Patent is:

1. In an automatic gas operated gun, a barrel having a bore, a lug projecting from the barrel and having a longitudinal passage extending therethrough and parallel to the bore and a second passage communicating between the bore and the longitudinal passage, said lug also having a valve-chamber concentric with said second passage, a valve seat in the second passage, internal threads in the walls of said valve-chamber, a guide sleeve having external and internal threads received by said valve-chamber, a tumbler-shaped check-valve supported within said guide sleeve and engaging said valve seat, a spiral spring within said valve and abutting thereto, a plug having threads received by said guide sleeve and serving as an abutment for the other end of said spiral spring, and means for equalizing gas pressure on the inside and outside of said check-valve.

2. In an automatic gas operated gun, a barrel having a bore, a lug projecting from the barrel and having a longitudinal passage extending therethrough and parallel to the bore, internal threads at each end of said passage, said lug also having a second passage communicating between the bore and said longitudinal passage, said lug also having a valve-chamber, a spring-pressed check-valve supported within the chamber and normally closing said second passage, a cylinder provided with externally threaded ends received by the rear end of said longitudinal passage, a piston having a longitudinally split body and a ball-socket therein and adapted to move within said cylinder, a piston-rod having a ball-terminal received by said ball-socket, a guide cap threaded onto the rear end of the cylinder, said cylinder having an action spring and abutting against said piston and said guide cap, said cylinder having an exhaust port, and means on the rear end of said piston-rod including a crosshead for further connections.

3. In an automatic gas operated gun, a barrel having a bore, a lug projecting from the barrel and having a longitudinal passage extending therethrough and parallel to the bore, internal threads at each end of said passage, said lug also having a second passage communicating between the bore and said longitudinal passage, said lug also having a valve-chamber, a spring-pressed valve within the chamber normally closing said second passage, a cylinder having externally threaded ends received by the rear end of said longitudinal passage and also having a main exhaust port communicating with the atmosphere, a piston having its main body longitudinally split into halves adapted to move within said cylinder, a ball-socket within said split piston, a piston-rod having a ball-terminal received by said ball-socket, a plurality of bull-rings and a nut adapted to bind said split piston together, a guide cap attached to the rear end of the cylinder, a spiral spring abutting said piston and said guide cap, and means on the piston-rod for further connections.
4. In an automatic gas operated gun, a barrel having a bore, a lug projecting from the barrel and having a longitudinal passage extending therethrough, internal threads at each end of said passage, said lug also having a second passage communicating between the bore and said longitudinal passage, said lug also having a valve-chamber, a spring-pressed check-valve in the chamber normally closing said second passage until opened by gas pressure from said bore, a cylinder attached to the rear end of said longitudinal passage, a piston in the cylinder, a piston-rod joined to the piston, a spiral spring bearing against the rear of said piston, said cylinder having a main exhaust port, a cylindrical reservoir threaded into the front end of said longitudinal passage, a spring-pressed relief valve connected to the reservoir, said reservoir adapted to receive and retain gases under pressure from said bore for causing said piston to move against said spiral spring, and means on the piston-rod including a crosshead for further connections.
5. In an automatic gas operated gun, a barrel having a bore, a lug projecting from the barrel and having a longitudinal passage extending therethrough and a second passage connecting the bore with the first mentioned passage, said lug also having a valve-chamber, a spring-pressed check-valve in said chamber normally closing said second passage until opened by gas pressure from said bore, a cylinder threaded into the rear end of said longitudinal passage, a piston in the cylinder, said cylinder having an exhaust port, a cylindrical gas reservoir threaded into the front end of said longitudinal passage, a spring-pressed relief valve connected to said reservoir normally closed until opened by excessive pressure within said reservoir, an auxiliary exhaust valve normally open by spring pressure carried within said relief valve, said auxiliary exhaust valve adapted to be closed by means of gas pressure from said reservoir and to open again when the piston in said cylinder has opened said exhaust port, means for enclosing and supporting said relief and exhaust valves including a cap threaded onto said reservoir, and means for connecting the piston to a breech mechanism including a piston-rod having a ball-terminal at one end and a cross-head at its opposite end.
6. In an automatic gas operated gun, a barrel having a bore, a lug projecting from the barrel and having a longitudinal passage extending therethrough and a second passage connecting the bore with said first mentioned passage, said lug also having a valve-chamber, a spring-pressed check-valve located in said chamber and normally closing said second passage, a cylinder threaded into the rear end of said longitudinal passage, a piston movable within said cylinder, a cylindrical gas-reservoir threaded into the front end of said longitudinal passage, a relief valve connected to said reservoir, a one-way control valve in said second passage, a semi-circular collar on said control valve, said lug having a semi-circular recess adapted to receive said collar, a hinged spring-pressed lever on said control valve adapted for regulating gases passing through said second passage to fill said reservoir while said relief valve limits the pressure thereof, said piston acted on by gas pressure from said reservoir, and means for connecting said piston to a breech mechanism, all substantially as shown and described.

HALVOR OLSEN EIANE.
